ATTORNEYS.

UNITED STATES PATENT OFFICE.

JOHN H. SHAW, OF NEW HAVEN, CONNECTICUT, ASSIGNOR TO THE SARGENT & COMPANY, OF SAME PLACE.

KNOB ATTACHMENT.

SPECIFICATION forming part of Letters Patent No. 606,590, dated June 28, 1898.

Application filed March 5, 1898. Serial No. 672,697. (No model.)

To all whom it may concern:

Be it known that I, JOHN H. SHAW, a resident of the city and county of New Haven, in the State of Connecticut, have invented a new and useful Improvement in Knob Attachments, of which the following is a full, clear, and exact description when taken in connection with the accompanying drawings, which form a part thereof, and in which—

10 Figure 1 represents a side elevation of a knob and spindle embodying my invention, the sleeve being shown in longitudinal section. Fig. 2 is a longitudinal vertical section through the knob; Fig. 3, an end view of the 15 knob by itself; and Figs. 4, 5 and 6, similar views of the sleeve, knob-shank, and locking-washer, respectively.

In all figures similar letters of reference represent like parts.

20 This invention relates to door-knobs, and more particularly to that class of knobs which may be accurately adjusted longitudinally on the spindle without the use of screws and be secured against any possible disadjustment 25 during the ordinary movements of the knob in operating the lock of the door.

The invention consists in the novel combination of the various portions of the knob with the spindle by which the former is easily 30 and accurately adjusted against the escutcheons of the door and prevented from accidental displacement.

In the drawings, A represents a door-knob, and B a spindle separate therefrom, rectangular in cross-section, the corners b being screw-threaded in well-known manner. The knob is provided with a rectangular axial perforation a, corresponding to the spindle B, which is adapted to be received therein, Fig. 2. 35 The knob-shank C is formed separate from the knob and is internally threaded, as shown at c, to mesh with the screw-threading b of the spindle. At one end of the shank C is an annular flange c', on the inner side of which are 40 a series of recesses or scallops c², arranged radially and equidistant from the center of the shank.

A flat interlocking washer D is provided with a central rectangular perforation d, corresponding with the cross-section of the spin-

45 dle B, and on its periphery are two oppositely-disposed lugs d', rounded to correspond with the recesses c² of the shank C, into which they are adapted to fit.

A hollow cylindrical sleeve E has formed 55 at one end an internally-extending flange e, and at the other end is internally threaded at e' to mesh with external threading a' on the hub of the knob.

The parts are assembled by first slipping 60 the sleeve E over the shank C, so that their respective flanges e and c' are in engagement. The shank C is then screwed onto the spindle to its proper position and the interlocking washer D slipped on the spindle, so that the 65 lug d' will fit in two of the recesses c² of the interior of the flange c'. The whole washer thus fits within the flange c', as shown in Fig. 2, and the shank is held against rotation 70 while the washer is in such position. To hold 75 the washer, the knob A is slipped on the spindle into juxtaposition with the washer D and end of the flange c' of the shank C, while the sleeve E is screwed on the hub of the knob and holds the parts together in engagement, Figs. 1 and 2. The shank is held rigidly on the spindle B until the sleeve E is unscrewed from the knob A, the knobs A withdrawn from the spindle, and the washer D removed from its position in the end of the 80 shank C.

Having now described my invention, what I claim, and desire to secure by Letters Patent, is—

1. In a door-knob, the combination with the 85 knob; of the spindle formed separate therefrom; an independent knob-shank, adapted to be screwed onto said spindle; an interlocking nut capable of longitudinal movement on said spindle but incapable of rotation independent thereof; means for locking said nut with said shank, and a sleeve adapted to fit loosely over said nut and be secured to said knob and shank, substantially as described.

2. In a door-knob the combination with a 95 knob; of a separate spindle substantially square in cross-section, with threaded corners of its square cross-section; an independent knob-shank adapted to be screwed onto said spindle, and having interior recesses at one 100

end; an interlocking nut adapted to slide on said spindle but incapable of rotation independent thereof, being provided with lugs adapted to engage in said recesses of said shank; and a sleeve adapted to engage said shank and knob and hold them together, substantially as described.

In witness whereof I have hereunto set my hand this 24th day of February, A. D. 1898.

JOHN H. SHAW.
